UNITED STATES PATENT OFFICE

GEORGE GODDU, OF WINCHESTER, MASSACHUSETTS, ASSIGNOR TO UNITED SHOE MACHINE CORPORATION, OF PATERSON, NEW JERSEY, A CORPORATION OF NEW JERSEY

METHOD OF MAKING SHOES

Application filed July 19, 1929. Serial No. 379,419.

This invention relates to methods of making shoes and is herein exemplified with special reference to methods of making turn shoes.

5 In the manufacture of turn shoes, an upper and a suitably channeled sole are assembled inside out upon a last, the upper is then lasted over the sole, and the shoe sewed either all the way round the periphery of the sole as in a 10 sewed seat turn or about the shank and forepart from breast line to breast line as in a nailed seat or open seat turn. The shoe is then removed from the last and turned the other side out. A turn shoe of either kind is 15 provided with a shank piece which consists of a filler piece of leather or leatherboard having the size and shape of the shank and heel-seat portion of the last bottom and, usually also, a shank stiffener of steel which 20 is secured to the leather or leatherboard piece, the stiffener having a longitudinal curvature similar to that of the shank portion of the last. In the case of a sewed seat turn shoe, the shank piece is placed in the shoe after it 25 is turned and is secured by glue or by a tack at the heel-seat, or both. In the case of an open seat turn shoe, the shank piece is usually inserted after the forepart of the shoe has been turned and forced on to the second last 30 and before the rear part is drawn over the rear end of the last. A shank piece so inserted may be temporarily secured in place by a tack driven through the shank piece and into the last, this tack being for the purpose 35 of holding the shank piece in place until the lasting operation is performed and being then withdrawn. When the shank piece is placed upon the second last it may be temporarily secured thereto by one or more headless tacks so that when the last is withdrawn 40 the headless tacks will be removed with it, they in the meantime having served to hold the shank piece in place during the heel-seat lasting operation. Of course, in the operation 45 of lasting the heel-seat or attaching the heel, the rear end of the shank piece will be firmly secured in place. Its forepart, however, is usually inadequately secured, the glue frequently failing to hold.

50 Objects of this invention are to provide a

method of making shoes by which the front end of the shank piece may be firmly and permanently secured in place, prior to the operation of lasting the heel-seat, by fastenings which do not penetrate the sole and are not visible on the exterior of the shoe.

In one aspect the invention consists in attaching a shank piece to a turn shoe while it is still inside out, the shank piece being thus held in place during the subsequent lasting operation and during the wear of the shoe. In another aspect the invention consists in securing the front end of a shank piece to a turn shoe by a fastening or fastenings driven through the front end of the shank piece and into the sole in such a manner that they do not penetrate the sole. As illustrated, a metallic fastening is so driven that it becomes clinched in the body of the sole. Since the shank piece has a longitudinal curvature corresponding to the longitudinal curvature of the shank portion of the last and is placed upon the turn shoe before it is turned, it is illustrated as positioned with its convex face uppermost and hence engages the shoe bottom only at its two ends. This condition, however, does not interfere with the attachment of the forward end of the stiffener and the exposed face of the sole of the turn shoe before it is turned in the manner described. Preferably the fastenings used are curved staples inserted at opposite corners of the front end of the shank with their bars extending transversely of the shoe and with their legs curved in planes extending lengthwise of the shoe and curved back toward the face of the sole through which they entered, being thus located in the body of the sole without penetrating the sole.

55 In the drawing,

Fig. 1 is a perspective view of a turn shoe in unturned condition having a shank piece secured at its forward end to the sole, and

Fig. 2 is a longitudinal section of the shoe and last after the shoe has been turned, placed upon the second last, and the heel-seat lasted.

The illustrated method of making turn shoes in which a shank piece is secured to the shoe before the shoe is turned, consists in

assembling an upper 10 and a suitably channeled sole 12 on a last 14 in the usual manner, the upper and sole being of course inside out. The upper is then lasted over the sole and sewed thereto by a seam 16 extending about the periphery of the shank and forepart of the shoe substantially from breast line to breast line in an open seat shoe, as illustrated, or entirely about the periphery of the shoe in the case of a sewed seat. At this stage in the manufacture of the shoe, a shank piece 18 is placed upon the shoe bottom with its rear end substantially flush with the end of the last and with its longitudinal convexity outward and is secured at its front end to the sole 12 by staples 20 which extend through the shank piece adjacent to the opposite corners of the front end thereof and into the sole, the legs of the staples being bent in the operation of driving so that they become clinched in the body of the sole instead of extending through the sole, as illustrated in Fig. 2; that is, the legs of the staples do not penetrate the face of the sole which is exposed in the completed shoe, that face being therefore intact.

The machine employed for inserting the staples may be similar to that disclosed in United States Letters Patent No. 1,742,499, granted January 7, 1930, upon my application.

The shoe is then turned, relasted, and completed in the usual manner. In the case of an open seat shoe, the upper, counter and lining at the rear end of the shoe will be worked over the rear end of the shank piece 18 and secured by tacks 22, as illustrated in Fig. 2, to effect the heel-seat lasting of the shoe, the staples 20 serving to hold the shank piece in place during this operation as well as throughout the life of the shoe.

Having thus described my invention, what I claim as new and desire to secure by Letters Patent of the United States is:

1. That improvement in methods of making turn shoes which comprises working an upper including a counter inside out over a sole upon a last, securing the upper and sole permanently together, and then before the shoe is turned securing a shank piece at its front end to the sole adjacent to the ball line.

2. That improvement in methods of making turn shoes which comprises working an upper inside out over a sole upon a last, securing the upper and sole permanently together, and before the shoe is turned securing a shank piece at its front end to the sole by curved metallic fastenings driven through the shank piece and into but not through the sole, said shank piece being longitudinally curved and having the shape it is to have after the shoe is turned.

3. That improvement in methods of making turn shoes which comprises working an

upper and counter inside out over a sole upon a last, securing the upper and counter permanently to the sole, and before turning the shoe securing a shank piece at its front end to the sole by metallic fastenings driven through the shank piece and into the sole in such a manner that the fastenings are clinched in the body of the sole without penetrating the surface of the sole which is next to the last.

4. That improvement in methods of making turn shoes which comprises working an upper inside out over a sole upon a last, sewing the upper to the sole, placing a longitudinally curved shank piece upon the shank portion of the shoe with its rear end flush with the end of the last and with its longitudinal convexity outward, then securing the front end of the shank piece to the shoe by staples so driven that the legs of the staples extend through the shank piece and into the sole and are clinched in the body of the sole without extending through the sole, turning the shoe, and conforming the sole to the curve of the shank piece.

5. That improvement in methods of making turn shoes which comprises working an upper inside out over a sole upon a last, securing the upper to the sole, placing a longitudinally curved shank piece upon the shank portion of the shoe with its rear end flush with the end of the last and with its longitudinal convexity outward, then securing the front end of the shank piece to the shoe by staples so driven that the legs of the staples are curved in the sole and do not penetrate that surface of the sole which is outermost in the completed shoe, turning the shoe, and conforming the sole to the curve of the shank piece.

6. That improvement in methods of making turn shoes which comprises attaching the front end of a longitudinally curved, rigid shank piece to the sole by a plurality of staples driven with their bars extending transversely of the shoe and with their legs curved longitudinally of the shoe and embedded in the sole without appearing on that face of the sole which is exposed in the completed shoe.

In testimony whereof I have signed my name to this specification.

GEORGE GODDU.
